Gustave L. LeRoy

INVENTOR

BY *Victor J. Evans*

ATTORNEY

UNITED STATES PATENT OFFICE.

GUSTAVE L. LE ROY, OF KANSAS CITY, MISSOURI.

SCREEN.

1,398,869.

Specification of Letters Patent. Patented Nov. 29, 1921.

Application filed August 24, 1920. Serial No. 405,594.

To all whom it may concern:

Be it known that I, GUSTAVE L. LE ROY, a citizen of the United States, residing at Kansas City, in the county of Jackson and State of Missouri, have invented new and useful Improvements in Screens, of which the following is a specification.

This invention relates to a frame for holding the wire mesh used for screening windows, the principal object of the invention being to make the frame adjustable to fit different sizes of windows and to provide means for clamping the screen to the frame so that the use of tacks and the like is eliminated.

Another object of the invention is to provide means for removably holding the frame in the window.

A further object of the invention is to provide means whereby the edges of the mesh are held between the parts of the frame.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a front view of the frame.

Fig. 2 is a rear view thereof.

Fig. 3 is a section on line 3—3 of Fig. 1.

Fig. 4 is a fragmentary view showing parts of the frame separated.

As shown in these views, the frame is formed of the four pairs of corner pieces 1, the two pairs of connecting side bars 2 and the two pairs of connecting end bars 3. The corner pieces are simply angle plates which are arranged in pairs and are adapted to receive the corners of the wire mesh, shown at 4, between them. The ends of these corner pieces are provided with slots 5 and the side and end bars are provided with spaced holes 6 which extend throughout their lengths.

The side and end bars are adapted to overlap the corner pieces with the ends of the corner pieces lying between the said bars. The parts are clamped together by the screw bolts 7 passing through the holes and slots 6 and having the nuts 7' engaging their ends.

It will thus be seen that the frame can be

made of different dimensions by adjusting the side and end bars relatively to the corner pieces and holding them in adjusted position by the bolts and nuts. It will also be seen 60 that the edges of the wire mesh are held between the parts of the frame so that the lower edges are hidden from view.

I provide the side and end bars with inwardly extending flanges 8 for gripping the 65 wire mesh when the parts are in clamping position. These side and end bars are made wider than the corner pieces so that the flanges will also engage the inner edges of these corner pieces.

The means for holding the frame in the window comprises a pair of spring controlled dogs 9 pivoted to the corner pieces at one end of the frame and a spring plunger 10 carried by one of the corner pieces at the 75 other end of the frame. The dogs are each provided with a laterally extending point 11 for engaging the window frame and metal sockets may be placed in the window frame for receiving these points if desired. The 80 spring plunger engaging the sill of the window will frictionally hold the lower end of the frame in place. By raising this plunger the frame may be swung outwardly or inwardly, the points 11 acting as pivots or the 85 frame can be entirely removed from the window by pressing the lower ends of the dogs inwardly against the action of the spring to release the points from the window frame. Instead of using the bolts and nuts shown I 90 may use thumb screws and make some of the holes in the side and end pieces screw threaded to receive said bolts.

It is thought from the foregoing description that the advantages and novel features 95 of my invention will be readily apparent.

I desire it to be understood that I may make changes in the construction and in the combination and arrangement of the several parts, provided that such changes fall within 100 the scope of the appended claims.

What I claim is:

1. A screen supporting frame of the character described comprising corner pieces of angle shape, pairs of side and end connecting 105 bars forming the intermediate frame members, inwardly projecting flanges provided on the inner edge of said side and end bars, means for holding the frame in the window, including spring controlled dogs pivoted to 110 the corner pieces at one end of the frame and having laterally extending points, and a

spring plunger engaging the sill of the window.

2. A screen supporting frame of the character described comprising four pairs of corner pieces of angle shape having slots formed therein, pairs of side and end connecting bars forming the intermediate frame members and having openings formed there-

in, said side and end bars overlapping the corner pieces and the ends of the corner 10 pieces lying between the side bars, means for clamping the parts together, inwardly extending flanges provided on the side and end bars for gripping the wire mesh.

In testimony whereof I affix my signature. 15
GUSTAVE L. LE ROY.
